CLAIM

The ornamental design for a holding strap for wireless ear-bud style earpieces, as shown and described.

DESCRIPTION

FIG. 1 is a front perspective view of a holding strap for wireless ear-bud style earpieces showing my new design; FIG. 2 is a rear perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof;

FIG. 9 is a right side elevational view thereof with stems of the wireless ear bud style earpieces separated from the holding strap; and,

FIG. 10 is a right side elevational view thereof with the stems of the wireless ear-bud style earpieces received in the holding strap.

The holding strap for wireless ear-bud style earpieces is shown with a symbolic break in its length. The appearance of any portion of the article between the break lines forms no part of the claimed design.

The broken lines showing the earpieces in FIGS. 9 and 10 depicts environment and form no part of the claimed design.

1 Claim, 10 Drawing Sheets
